Willis E. Williams, Shelbyville, and Edward W. Harrison, Indianapolis, Ind., assignors to Chambers Corporation, a corporation of Indiana

Application January 14, 1950, Serial No. 7,241

Term of patent 14 years

(Cl. D81—25)

To all whom it may concern:

Be it known that we, Willis E. Williams and Edward W. Harrison, citizens of the United States and residents, respectively, of Shelbyville, in the county of Shelby, and Indianapolis, in the county of Marion and State of Indiana, have invented a new, original, and ornamental Design for a Backsplash Panel for a Cooking Range, of which the following is a specification, reference being had to the accompanying drawing, forming part thereof.

Figure 1 is a front elevation of a backsplash panel for a cooking range, showing our new design;

Fig. 2 is a top plan view thereof;

Fig. 3 is a bottom plan view thereof; and

Fig. 4 is a vertical section taken along the line 4—4 of Fig. 1.

We claim:

The ornamental design for a backsplash panel for a cooking range, as shown.

WILLIS E. WILLIAMS.
EDWARD W. HARRISON.
